UNITED STATES PATENT OFFICE.

JOHN D. BRESNIHAN, OF MONTGOMERY, ALABAMA.

IMPROVEMENT IN BOILER FIRE-EXTINGUISHERS.

Specification forming part of Letters Patent No. **138,068**, dated April 22, 1873; application filed February 8, 1873.

To all whom it may concern:

Be it known that I, JOHN D. BRESNIHAN, of Montgomery, in the county of Montgomery and State of Alabama, have invented a new and Improved Boiler Fire-Extinguisher, of which the following is a specification:

Figure 1 is an elevation of the steam-boiler with my fire-extinguisher applied to it. Fig. 2 is an enlarged vertical section of the extinguisher.

Similar letters of reference indicate corresponding parts.

The object of my invention is to supply steam-boilers with an instrument by the use of which the fire may be expeditiously reduced or extinguished, curtailing thereby expenses and diminishing accidents. My invention consists of a hollow tube extending through both sheets of a steam-boiler, with lateral perforations.

The aperture of the tube toward the fire may be opened or closed by a movable bolt acting as a valve, which either allows the admission of the water from the boiler or shuts off the same, giving thereby perfect and quick control over the fire in the fire-box.

In the drawing, A represents the steam-boiler; B, the fire-box. A tube, C, Figs. 1 and 2, connects the sheets of the boiler, being tightly secured or otherwise fitted therein. The hollow of the tube is, toward the fire-box, reduced in width in the shape of a funnel, and opens by an aperture, a, to the fire. A requisite number of holes, b, perforate the tube, and establish the admission of the steam from the boiler to the fire-box. A bolt or shaft, D, of smaller diameter than the tube, moves freely therein by screwing into a projection, d, of the tube, applied at the outside

of the boiler, the motion being produced by a crank or wheel, E. A conical head, c, of bolt D acts like a stopper or valve on the funnel-shaped part of tube C, opening or closing the aperture a, according to the turning of wheel E. By loosening the screw-bolt D the valve c is gradually withdrawn from the aperture a, allowing the water to pass through the perforations b and aperture a to the fire-box. By turning bolt D in the other direction, the aperture a is closed, and the steam connection interrupted. By the admission of a greater or less quantity of water the fire may, at will, be either reduced or extinguished, and thereby a full control over the same be obtained. If the ends of the tube C are properly attached by screws to the inside of the boiler, the middle portion of the tube C, including that perforated by holes, may be dispensed with, if in practice it is found to impede the operation of bolt and valve D c.

Having thus described my invention, I claim as new and desire to secure by Letters Patent—

1. The tube C, with perforations b and aperture a, in connection with the bolt and valve D c, substantially as and for the purpose described.

2. The tube C provided with a bolt, and valve D c, and perforations a b, in combination with the furnace or fire-box of a boiler, and the steam and water space formed contiguously thereto between the sheets of the boiler, as shown and set forth.

JOHN DANNIEL BRESNIHAN.
